Primary Examiner — Kendra Leslie Hamilton(74) *Attorney, Agent, or Firm* — Greer Burns & Crain Ltd.(57) **CLAIM**

The ornamental design for a feeding bottle, as shown and described.

DESCRIPTION

FIG. 1 is a perspective view of a feeding bottle showing the new design;

FIG. 2 is a side elevational view thereof;

FIG. 3 is an opposite side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is an exploded perspective view thereof.

The broken lines in FIGS. 1-2 and 4-8 define the environmental structure of the claimed design and form no part thereof.

1 Claim, 7 Drawing Sheets(56)
